US0D1006531S

(12) **United States Design Patent** (10) Patent No.: **US D1,006,531 S**
(45) Date of Patent: ** *Dec. 5, 2023

(54) **REMOVABLE JAR OF A PORTABLE BLENDER**

(71) Applicant: **BlendJet Inc.**, Benicia, CA (US)

(72) Inventor: **Ryan Michael Pamplin**, San Juan, PR (US)

(73) Assignee: **BlendJet Inc.**, Benicia, CA (US)

(*) Notice: This patent is subject to a terminal disclaimer.

(**) Term: **15 Years**

(21) Appl. No.: **29/763,134**

(22) Filed: **Dec. 21, 2020**

Related U.S. Application Data

(63) Continuation of application No. 29/715,453, filed on Dec. 2, 2019, now Pat. No. Des. 908,428.

(57) **CLAIM**

The ornamental design for a removable jar of a portable blender, as shown and described.

DESCRIPTION

FIG. 1 is a front view of a removable jar of a portable blender showing the new design; and,

FIG. 2 is a front-left perspective view thereof.

The surface(s) or portion(s) of the claimed design that would normally be visible but are not shown in the drawing or described in the specification of the present application form(s) no part of the claimed design.

1 Claim, 2 Drawing Sheets
